UNITED STATES PATENT OFFICE.

OTIS E. BROWN, OF BROCKTON, MASSACHUSETTS, ASSIGNOR TO THE SINGER MANUFACTURING COMPANY, A CORPORATION OF NEW JERSEY.

SEWING-MACHINE.

1,123,237.

Specification of Letters Patent

Patented Jan. 5, 1915.

Original application filed February 27, 1908, Serial No. 480,338. Divided and this application filed March 4, 1910. Serial No. 547,248.

To all whom it may concern:

Be it known that I, OTIS E. BROWN, a citizen of the United States, residing at Brockton, in the county of Plymouth and State of Massachusetts, have invented certain new and useful Improvements in Sewing-Machines, of which the following is a specification, reference being had therein to the accompanying drawings.

10 This application is a division of the application upon which my Patent No. 1,002,217, of September 5, 1911, was granted; and the present invention has for its object to provide a simple and effective means for lifting 15 the presser-foot and the stitch-setting implement uniformly regardless of the varying thickness of the work.

According to the present invention the presser-bar carries both the presser-foot and 20 the stitch-setter, and is embraced by an end-wise-movable sleeve which sustains a fulcrum for a cramping lever having a jaw adjacent said fulcrum for engaging the presser-bar, means being provided for rocking 25 the cramping lever in the production of each stitch to successively grip and release the presser-bar.

The invention also includes special means for supporting and for imparting to the 30 stitch-setter differential movements relative to those of the presser-foot.

In the drawings, Figure 1 is a rear side elevation of a machine embodying the present improvements, with the frame partly in 35 section, and Fig. 2 is an elevation representing the front end of the machine. Fig. 3 is an elevation of the actuating means for the presser-foot-lifting rock-shaft. Fig. 4 is a perspective view upon a larger scale of the 40 presser-bar and its lifting means, and Fig. 5 a perspective view of a portion of the presser-bar lifting means. Figs. 6 and 7 are perspective views representing the lower portion of the presser-bar, the presser-foot, 45 the stitch-setter and the sustaining and actuating means for the latter, these views being taken respectively from above and below such parts.

The frame of the machine is shown constructed with the hollow standard 1 with cylindrical work-supporting arm or horn 2 and hollow overhanging bracket-arm 3 terminating in the usual head 4. The needle 5 is mounted in the reciprocating needle-bar

6 journaled in the upper and lower bearings 7 of the jogging needle-frame 8 whose lateral movements in the line of seam take place while the needle is in its lower position for advancing the work to space the stitches. The needle-bar carries the usual 60 collar 9 connected by means of the pitman 10 with a crank-arm of the rock-shaft 11 having suitable connections with the upper end of a link-bar 12 journaled in the swinging yoke 13 pivotally mounted upon the 65 rock-shaft 14 and provided with a strap 15 embracing the crank 16 in the main-shaft 17 suitably journaled in the standard 1. Co-operating with the needle 5 is the shuttle 18 provided with the barrel-shaped thread-case 70 19, and actuated by means of the driver 20 fixed upon the forward end of the rock-shaft 21 which is connected by suitable means, including the pitman 22, with the link-bar 12 so as to actuate the shuttle synchronously 75 with the needle movements.

The presser-foot 23 is formed with the usual elongated needle-aperture, and is provided with a shank 24 having at its upper end a transversely grooved member adjustably secured by means of the fastening screw 26 upon a correspondingly shaped seat 27 formed upon a collar 27 fixed to the lower end of the presser-bar 28. The collar 27 is formed with a slot 25 to receive the screw 80 26. The presser-bar is fitted to suitable bearings in the head of the bracket-arm and is provided at the top with a shouldered cap 29 to receive the lower end of a coiled compression spring 30 whose opposite end is 90 similarly fitted to a shouldered plug 31 formed upon the lower end of the adjusting screw 32 secured against rotation by the lock-nut 33 in the threaded boss 34 of a thrust-rod 35 secured in a boss 36 upon the 95 top of the bracket-arm member 4. The presser-bar is flattened upon one side at 28° and has slidingly mounted thereon the sleeve 37 provided with laterally projecting spaced ears 38 between which is pivoted by means 100 of the pin 39 the rock-lever 40 having at its lower end a slot or fork 41 within which is pivoted by means of a pin 42 the cramping lever 43 having upon one side of its fulcrum-point the jaw 44 adapted to enter a 105 slot 45 in the lower end of the sleeve 37 and engage the flattened portion 28° of the presser-bar. The supporting lever 40 is formed with

an upward extension or lug 46 in which is adjustably secured and locked by means of the nut 47 the threaded outer end of a stop-screw-pin 48 whose point passes through a lateral aperture 49 in the sleeve 37 for engagement with the flattened side 28^x of the presser-bar. The stop-pin 48 serves not only as a clamping member of the swinging lever 40, but serves to limit the movement of the latter to determine the effective position of the pivotal pin 42 and thus to control the timing of the operative engagement of the clamping members of both the levers 40 and 43 under the uniform lifting movements imparted to the latter by its connections with the actuating eccentric 59.

The apertured outer end of the cramping lever 43 embraces a pin 50 by means of which it is pivotally connected with a forked lower end of a link 51 whose upper end is pivotally connected by means of a pin 52 with a lateral crank-arm 53 secured to the forward end of a rock-shaft 54, journaled within and longitudinally of the bracket-arm 3 and having fixed upon its rearward end the lateral crank-arm 55 connected by means of the screw-stud 56 with the eccentric-rod 57 having at its lower end the strap 58 embracing the actuating eccentric 59 upon the main or driving shaft 17. The eccentric 59 imparts to the rock-shaft 54, through the eccentric-rod 57 and crank-arm 55, rocking movements which are communicated to the cramping lever 43 through the crank-arm 53 and link 51, which movements are ineffective for the greater part, but which become effective in lifting the presser-bar and the presser-foot when the cramping lever 43 is raised sufficiently to seat its jaw 44 firmly upon the flattened portion 28^x of the presser-bar, which causes these parts to become locked together and to be lifted bodily in the continued upward movement of the link 51 with the crank-arm 53.

The presser-bar is adapted to rise independently of the sleeve 37 in order to permit the presser-foot to accommodate itself to different thicknesses of material without affecting the action of the lifting mechanism thereon, and the sleeve is normally pressed downward by a spring 60 surrounding the presser-bar and interposed between the top of the sleeve and a suitable abutment 55 above the same, whereby the forked lateral extension 40^x at the lower end of the lever 40, which embraces the presser-bar 28, is caused to normally rest upon the top of a series of washers 61 of yielding material 60 which are interposed between the same upon the presser-bar and the top of the lower presser-bar bearing, whereby noise and shock are prevented in the actuation of the presser-bar. The eccentric 59 is so set upon 65 the main-shaft 17 as to cause the lifting of

the presser-bar just as the needle is about to begin its lateral or feeding movement, so as to permit the work to be advanced by the needle without resistance.

Fixed upon the lower portion of the presser-bar 28 above the presser-foot shank is a block 62 formed with a split socket embracing the presser-bar and clamped thereon by means of the screw 63. The block is provided with a second split socket with adjacent spaced perforated ears 64 entered by the clamp-screw 65 for securing the same upon the lower end of a vertical slide-bar 66 journaled in the lower member of the bracket-arm head 4 and having fixed to its upper end the collar 67 with rigid lateral arm 68 carrying the roller-stud 69 against the lower side of which rests the flat wearing face upon the top of the forward portion 70 of a lifting rock-lever 71 fulcrumed at 72 upon the bracket-arm and having in its rearward end an eye 73 for attachment of a treadle-rod in a manner well known. As will be evident, the manual actuation of the lever 71 operates through the slide-bar 66 and the block 62 to raise the presser-bar independently of its automatically acting lifting means.

The block 62 is provided with a rearwardly and upwardly extending arm 74 having a split bearing 75 in which is adjustably secured by means of the clamp-screw 76 the hub 77 of a depending lever 78 carrying at its lower end a stud-screw 79 connected by means of a link 80 with a similar screw 81 tapped into a rearwardly projecting ear of a lever 82 having at its lower end a slot 83 entered by a fastening screw 84 tapped into the upper end or shank of a stitch-setting blade 85, whose lower end is shaped to embrace the individual stitches of a seam, intermediate the needle punctures, in a manner well known.

The upper end of the lever 82 is pivotally connected by means of the stud-screw 86 with the lateral arm 87 of a rocker 88 carrying the center-screws 89 which enter conical recesses in the opposite ends of the hub 77 of the lever 78, by means of which said rocker is mounted to oscillate upon the arm 115 74. The rocker 88 is provided with an upwardly projecting arm 90 connected by means of a screw-stud 91 with one end of a link 92 whose opposite end is connected by means of the screw-pin 93 with a depending crank-arm 94 fixed upon the forward end of the rock-shaft 54 and preferably formed integral with the crank-arm 53. The crank-arms 53 and 94 are so proportioned and arranged that the rocker 88 125 is oscillated to carry the stitch-setter through the slot 28^x in the presser-foot 23 and into operative relation with the work just after the needle has accomplished a feeding movement and has emerged from 130

the work, the stitch-setter remaining in contact with the work until the needle is descending into the forward end of the needle aperture in the presser-foot to make a new puncture. In order that the stitch-setter may have a lateral movement in the line of seam to avoid interference with the needle, the link 80 is made shorter than the crank-arm 87, whereby the stitch-setter is drawn backwardly by the link as said crank-arm rises to withdraw it from contact with the work, and is correspondingly advanced in its descending movement.

The support of the stitch-setter upon the block 62 rigidly connected with the presser-bar 28 causes it to partake of the rising and falling movements of the latter, and insures that both the presser-foot and the stitch-setter shall be disengaged from the work while the needle is performing its feeding movement, and it also insures that both shall be lifted clear of the work when the presser-foot is raised for the introduction or removal of the same.

25. To adjust the point of application of the stitch-setter 85 relatively to the needle-path, the lever 78 is provided with an ear 95 which is engaged upon the rearward side by an adjusting screw 96 carried by a depending ear 97 of the arm or standard 74 and upon the front side by the point of an adjusting screw 98 passing through a lateral ear 99 of the block 62. To adjust the fulcrum-point of the link 80 in the direction of seam, one or the other of the adjusting screws 96 and 98 is withdrawn to the required extent and the other advanced to press the depending ear 95 firmly against the same, the path of movement of the stitch-setter carrying lever 82 being thus modified to suit the requirements of the work in bringing the stitch-setter into exact register with the stitches.

From the foregoing description it will be observed that the machine herein shown and described contains not only common actuating mechanism for the clutch device including the cramping lever 43 intermittently engaging the presser-bar and the vibratory members 80 and 87 connected with the stitch-setter carrying lever 82, but has a common support, consisting of the presser-bar 28, for both the presser-foot and the stitch-setter, whereby they may be bodily lifted from and lowered into operative relation with the work by common automatically and manually controlled means, although under automatic control their rising and falling movements are differential. It will be further observed that, although the operative face of the presser-foot is substantially flat and that of the stitch-setter is arched, they constitute practically alternating pressers in their operation upon the work with similar function and mode of op-

eration although differing in specific effect upon the work.

Having thus set forth the nature of the invention, what I claim herein is:—

1. In a sewing machine, in combination, 70 a stitch-setting implement, a plurality of swinging arms connected with and sustaining said implement at spaced pivotal points, and actuating means whereby said implement is given bodily movements upon said 75 arms.

2. In a sewing machine, in combination, a stitch-setting implement, a plurality of swinging arms connected with and sustaining said implement at spaced pivotal points, 80 and means applied to one of said arms for imparting to it its swinging movements.

3. In a sewing machine, in combination, a stitch-setting implement, a plurality of swinging arms of different lengths each 85 connected independently of the other with said implement, and actuating means for imparting operative movements to said implement.

4. In a sewing machine, in combination, 90 a stitch-setting implement, a swinging support upon which said implement is pivotally mounted and positively confined to movement in a fixed path, an actuating rock-shaft, and connections between the same and 95 said support including a train of elements having permanent pivotal connections, whereby a positive connection is effected between the actuating rock-shaft and the stitch-setting implement and the latter derives from said rock-shaft reciprocatory movements which are positively controlled in both directions.

5. In a sewing machine, the combination with a presser-foot, a presser-bar to which 105 said presser-foot is attached, a stitch-setting implement, a movable support for said implement sustained by the presser-bar, and presser-bar lifting means, of an actuating rock-shaft, an arm fixed upon said rock-shaft and operatively connected with said 110 presser-bar lifting means, and a second arm fixed upon said rock-shaft and operatively connected with the stitch-setting implement for imparting operative movements 115 to the latter.

6. In a sewing machine, in combination, 120 a presser-foot, a presser-bar by which said presser-foot is carried, a fulcrum sustained by said presser-bar, a rocker mounted on said fulcrum and having a lateral arm, a stitch-setting implement pivotally connected with the lateral arm of said rocker, means including a swinging arm for controlling the movements of said stitch-setting implement, actuating means connected with said rocker, and lifting means for the presser-bar.

7. In a sewing machine, the combination with stitch-forming mechanism comprising 125

5 a needle and a coöperating loop-taker and means for actuating them, and a presser-foot, of a stitch-setting implement, a carrying lever therefor, a rocker mounted upon a fulcrum sustained in fixed relation with said presser-foot and having a vibratory arm connected to said carrying lever, a link of different length from said vibratory arm and spaced therefrom and also connected at 10 one end with said carrying lever, a fulcrum for the other end of said link and sustained in fixed relation with said presser-foot, and means for actuating said rocker to reciprocate the stitch-setting implement in a curved 15 path.

8. In a sewing machine, the combination with stitch-forming mechanism comprising a needle and a coöperating loop-taker and means for actuating them, and a presser-foot, of a stitch-setting implement, a carrying lever therefor, a rocker mounted upon a fulcrum sustained in fixed relation with the axis of movement of said rocker and having a vibratory arm connected to said carrying 20 lever, a link of different length from said vibratory arm and spaced therefrom and also connected at one end with said carrying lever, a fulcrum for the other end of said link sustained in fixed relation with the first 25 named fulcrum, means for adjusting the position of the fulcrum of said link, and means for actuating said rocker to reciprocate the stitch-setting implement in a curved path.

9. In a sewing machine, the combination with stitch-forming mechanism comprising a needle and a coöperating loop-taker and means for actuating them, a presser-foot, and a presser-bar by which said presser-foot is carried, of a bracket fixed to said presser-bar, a rocker fulcrumed upon said bracket and provided with a lateral crank-arm and with a second crank-arm, a stitch-setting implement, a carrying lever therefor, a pivotal connection intermediate said carrying lever 45 and the lateral crank-arm of said rocker, a fulcrum-stud carried by said bracket, a link connection intermediate said fulcrum-stud and said carrying lever for the stitch-setting implement, and actuating means connected 50 with the second arm of said rocker for imparting operative movements to the stitch-setting implement.

10. In a sewing machine, the combination with stitch-forming mechanism comprising a needle and a coöperating loop-taker and means for actuating them, a presser-foot, and a presser-bar by which said presser-foot is carried, of a bracket fixed to said presser-bar, a stitch-setting implement, a carrying 55 lever therefor, a pair of spaced substantially parallel vibratory members to which said carrying lever is pivotally connected, a rock-

shaft, actuating means therefor, two angularly arranged crank-arms fixed upon said rock-shaft, a connection intermediate one of 65 said crank-arms and one of said vibratory arms from which the stitch-setter derives operative movements, a spring applied to said presser-bar, a clutch device slidingly mounted upon said presser-bar, and an operative 70 connection between the second crank-arm of said rock-shaft and said clutch device whereby the presser-bar is lifted in opposition to said spring.

11. In a sewing machine, the combination 75 with stitch-forming mechanism comprising a needle and a coöperating loop-taker and means for actuating them, a presser-foot, and a presser-bar by which said presser-foot is carried, of a bracket fixed to said presser-bar, a stitch-setting implement supported by said bracket, means for imparting operative 80 rising and falling movements to said stitch-setting implement, a slide-bar attached to said bracket and disposed parallel with the presser-bar, a lateral stud or projection upon 85 said slide-bar, and a lifting lever adapted to engage said lateral stud or projection of the slide-bar in lifting the presser-bar with the presser-foot and stitch-setting implement. 90

12. In a sewing machine, in combination, a presser-foot, a presser-bar by which said presser-foot is carried, a fulcrum sustained by said presser-bar, a rocker mounted on 95 said fulcrum, a stitch-setting implement pivotally connected with said rocker, means for controlling the action of said stitch-setting implement, including an adjustable swinging arm whereby the point of application of 100 said stitch-setting implement may be varied 100 at will, actuating means connected with said rocker, and lifting means for the presser-bar.

13. In a sewing machine, in combination, a presser-foot, a presser-bar by which said 105 presser-foot is carried, a fulcrum sustained by said presser-bar, a rocker mounted on said fulcrum and having a lateral arm, a stitch-setting implement pivotally connected to the lateral arm of said rocker and having 110 a fulcrum movable relatively to the first named fulcrum, means for varying the position of the fulcrum for said stitch-setting implement, actuating means connected with 115 said rocker, and lifting means for the presser-bar.

In testimony whereof, I have signed my name to this specification, in the presence of two subscribing witnesses.
